4 Sheets-Sheet 1

This technical diagram illustrates a cross-sectional view of a circular mechanical assembly, possibly a bearing or seal. The outer boundary is a thick, concentric circular ring. Inside this ring, there are several key components and features:

- Central Components:** A central circular area contains a series of concentric dashed lines, suggesting a hub or a central bearing element.
- Mounting Features:** Four rectangular blocks, labeled 11, are positioned at the top, bottom, left, and right peripheries of the central area. Each block has a central hole and is secured to the inner ring by four bolts, with washers labeled 14 and lock washers labeled 15.
- Shaft and Support:** A vertical shaft or support structure, labeled 6, extends from the top of the central hub area through the top block 11.
- Outer Ring and Labels:** The outer ring is labeled with the number 7 at the top. The outer periphery of the ring features four circular holes, each marked with the number 2. The bottom hole is also marked with the number 2.
- Internal Labels:** Various internal parts are labeled with numbers:
  - 11: The rectangular blocks at the periphery.
  - 14: Washers used in the mounting.
  - 15: Lock washers used in the mounting.
  - 16: A label near the bottom center.
  - 17: A label on the right side.
  - 18: A label on the left side.
  - 19: A label on the top left.
  - 20: A label on the right side.
  - 21: A label on the bottom center.
  - 22: A label on the right side.
  - 23: A label on the left side.
  - 24: A label on the top center.
  - 25: A label on the bottom center.

Application July 29, 1938, Serial No. 222,051

4 Claims. (Cl. 280—33.15)

This invention appertains to new and useful improvements in couplings and more particularly to a coupling especially adapted for use in conjunction with trailers, and in other instances where a coupling of this character would be required.

The principal object of the present invention is to provide a coupling having universal movement and wherein the parts are so related as to substantially eliminate any chance of detachment.

Still another important object of the invention is to provide a coupling of the character stated which is constructed of a limited number of parts, but sturdy and not susceptible to the ready development of defects.

These and various other important objects and advantages of the invention will become apparent to the reader of the following specification.

20 In the drawings:

Figure 1 represents a top plan view of the coupling.

Figure 2 is a section on the line 2—2 of Figure 1.

Figure 3 is a fragmentary top plan view of the 25 bed.

Figure 4 is a top plan view with a portion broken away of a slightly modified form of the invention.

Figure 5 is a sectional view taken substantially on the line 5—5 of Figure 4.

30 Figure 6 is a bottom plan view of the upper ball section and attaching plate.

Referring to the drawings wherein like numerals designate like parts, it can be seen that numeral 5 represents the bed plate from which 35 extends a plurality of spokes 6, each of which is provided with a reduced end portion on which rests the annulus 7, which of course eliminates any excessive motion of the trailer.

The bed plate 5 is formed with the recess 8 in the bottom of which is the concavity 9 for receiving the lower portion of the ball connector 10.

The cap structure for holding the ball 10 in the pocket 8 and in proper connection with the bed plate 5 is made up of the pair of sections 45

11—11, each end of these sections 11—11 being provided with a transversely extending groove 12 in the end walls of the recess 8, so that when these grooves of the sections 11 and wall of the recess 8 are in

50 opposed relation, passageways are defined for the reception of the keys 13 which will fasten the cap plate sections in place and prevent detachment of the ball 10.

The keys 13 are provided with laterally disposed handles 14, each at one end, and these

handles can be swung downwardly against the plate 5 so that they will be interposed between one of the spokes 6 and an abutment lug 15 rising from the bed plate 5.

A short neck 16 extends upwardly from the ball 5 10 to connect to the trailer attachable plate 17, which is formed with openings 18 through which securing elements can be disposed for securing the plate in place.

The bed plate 6 is also formed with openings 19 10 through which securing means can be disposed to secure the bed plate to the lead vehicle.

Another form of the invention is shown in Figures 4, 5 and 6. In this form of the invention the base 20 has elevated laterally extending 15 spokes 21 the outer end of each of which is reduced as at 22 to define a shoulder portion for accommodating the annulus 23 which is secured to the ends of the spokes 21 by screws 24.

At the rear side of the base 20 a ramp 25 is 20 provided. This ramp is in the form of an inclined apron having the side wall portions 26 which extend upwardly and merge with the top of the base 20. The top of the base 20 is provided with the ball receiving socket 27 therein. The top of 25 the base 20 at approximately one-half of the diameter of the socket 27 is provided with the upstanding shoulder 28 which is complementary to the semi-circular upstanding shoulder 29 on the removable spoke 30 which is removable from 30 the annulus 23 by the detachment of the screw 31. As shown in Figure 4, the inner end of this spoke 30 flares out to form the head 32 which rests on the reduced underlying portion of the base 20 and has its shoulder portion 29 serving 35 in complement with the shoulder 28 the upper portion of the socket 27 for holding against displacement the upper ball section 33 which as is shown in Figure 6 is provided with a diametrically disposed channel 34 for receiving the upstanding rib 35 on the lower ball section 36. The upper section 33 of the ball has the shank 37 on which is the attaching plate 38.

Key members 39—39 similar to the keys 13 in Figure 2 extend through certain of the spokes 21 45 and also through grooves 40 in the side portions of the flared part 32 of the spoke 30 to prevent rising of this end portion of the spoke thus forming the socket for the ball sections 33 and 36 intact. The pins 39 are provided with laterally 50 disposed handles 41.

As can be seen in Figure 4, the base 20 has openings 42 therein for the reception of securing elements.

While the foregoing specification sets forth the 55

invention in specific terms, it is to be understood that numerous changes in the shape, size and materials may be resorted to without departing from the spirit and scope of the invention as claimed hereinafter.

Having described the invention, what is claimed as new is:

1. A coupling of the character comprising a bed plate, said bed plate being provided with a recess therein, a ball, structure attachable means on the ball, said ball being disposable in the pocket, a cap plate for embracing the ball and holding the ball in the recess, and detachable means between the cap plate and the bed plate, an annulus, spokes extending from the base to the annulus, one of said spokes being removable and having its inner end constructed to prevent displacement of the ball from the socket.

2. A coupling of the character described comprising a plate, an annulus attached to the plate, said plate being provided with a part socket, a spoke attached at one end to the annulus and provided at its opposite end with a part socket cooperative with the part socket of the plate,

and a structure attachable ball disposed between the said part sockets.

3. A coupling of the character described comprising a plate, an annulus attached to the plate, said plate being provided with a part socket, a spoke attached at one end to the annulus and provided at its opposite end with a part socket cooperative with the part socket of the plate, and a structure attachable ball disposed between the said part sockets, and a ramp extending from the plate at a position underlying the said spoke.

4. A coupling of the character described comprising a plate, an annulus attached to the plate, said plate being provided with a part socket, a spoke attached at one end to the annulus and provided at its opposite end with a part socket cooperative with the part socket of the plate, and a structure attachable ball disposed between the said part sockets, and detachable connecting means between the annulus and the spoke and between the plate and the part socket end of the spoke.

ELBERT S. MILLER.
